AMUSEMENT APPARATUS

3 Sheets-Sheet 2

This technical drawing illustrates a cross-sectional view of a mechanical assembly, possibly a pump or valve mechanism. The drawing is labeled 'FIG. 2.' in the top left corner. The assembly features a central vertical rod (50) with a handle (51) at the top. A horizontal rod (52) is attached to the top of the central rod. A vertical rod (53) is positioned to the right of the central rod. A curved component (54) is located at the bottom right. Various parts are labeled with numbers: 50, 51, 52, 53, 54, 55, 56, 57, 58, 59, 60, 61, 62, 63, 64, 65, 66, 67, 68, 69, 70, 71, 72, 73, 74, 75, and 76. The drawing uses hatching and cross-hatching to differentiate between different parts and materials.

AMUSEMENT APPARATUS

Leif Gösta Hellesen, Stockholm, Sweden

Application March 10, 1937, Serial No. 130,005

6 Claims. (Cl. 104—68)

This invention relates to amusement apparatus, and is more particularly concerned with public amusement apparatus of the type in which a bowl-like structure is arranged for rotation so that persons entering the bowl may move up the interior sides thereof, being maintained against falling by the action of centrifugal force.

Amusement apparatus of the type indicated is already known, but has had certain drawbacks. Thus in the usual way if a gallery were arranged for spectators, persons would be unwilling to enter the bowl due to the embarrassment of appearing before the spectators. On the other hand it is not generally found profitable merely to run the bowl with no spectators. It will also be clear that where no arrangements are made for spectators, persons who are uncertain whether to enter the bowl will have no opportunity of watching first how other people enjoy the amusement.

It is a primary object of the invention to evolve an apparatus which will overcome the objections set forth above. According to the invention amusement apparatus comprises a bowl, a closable entrance into said bowl to allow persons to reach the interior thereof, driving means for turning said bowl about a vertical axis, at least one gallery for spectators arranged adjacent the upper part of the bowl, and means for allowing spectators to look into the bowl, said means simultaneously serving to prevent persons within the bowl from seeing the spectators.

The annexed drawings illustrate several constructional embodiments of the invention.

Figure 1 being a sectional elevation of an amusement apparatus intended for dismantling when desired,

Figure 2, a view similar to Figure 1 of an embodiment of the invention intended to be set up permanently,

Figure 3, a detail of part of the apparatus shown in Figure 2,

Figures 4 and 5, respectively a side elevation and plan view of a device for aiding persons to maintain balance, and

Figures 6 and 7 being respectively side and plan views of a further construction of apparatus for aiding persons to maintain balance.

Referring first to the constructional embodiment of Figure 1, the bowl is generally indicated at 1, and it will be observed that it consists of several portions 1A, 1B, and 1C. The various parts form together a bowl which is approximately hemispherical in section but which has a plane portion 2 lying substantially horizontal. The side walls of the bowl slope upwards to a zone 3 which

is substantially vertical. A light portable structure 4 is arranged around the bowl, there being a roof 5. An annular platform 6 is arranged to support spectators, and a stairway 7 allows the platform 6 to be reached from normal ground level indicated at 8.

The bowl 1 is arranged for rotation upon an annular trackway afforded by an H-section member 9 carried upon a bed-plate 10. The underside of the bowl has secured to it a plurality of rollers 10 11 which run on the trackway 9. The centre of the bowl is traversed by a shaft 12 which carries a bevel pinion 13. The bevel pinion 13 meshes with a similar pinion 14 arranged for driving by an electric motor 15.

The sections of the bowl 1 are bolted together and further stayed with the aid of a flexible wire rope 16, and in one of the sections an aperture is formed and is adapted to be closed by a door 17 supported on hinges 18. A short stairway 19 is arranged at one side of the apparatus to allow persons to enter through the doorway 11. The upper side of the bowl is closed by a roof member 20 through which a lamp 21 is arranged to project. Near its periphery the roof-like member 20 has a plurality of inserted frames 22, each frame receiving a sheet of semi-transparent mirror glass 23.

In the operation of the described apparatus persons are allowed to enter the bowl through the doorway 11, and persons may also ascend the stairway 7 and stand or sit around upon the platform 6. There is no lighting in the spectators' gallery, or if there be lighting it is subdued. However, within the bowl there is the lamp 21 which throws considerable light over the interior of the bowl. It will be understood that since there is a greater lighting intensity at the interior of the bowl, the spectators will be able to see through the semi-transparent glass windows 23, but such

windows will act as mirrors when viewed from the interior of the bowl. The persons entering through the door 17 will thus be unable to see the spectators. The bowl 1 is set in motion through the intermediary of the gear train 14, 13 driven by the motor 15. The door 17 is closed once the persons are within the bowl and the latter has been set in rotation. The action of centrifugal force will cause persons within the bowl to be moved outwards towards the upwardly curving walls of the latter. As the speed of the bowl increases the persons within will be able to mount the sloping walls, and will even be able to assume a position approaching the horizontal without feeling discomfort.

- As will be appreciated, the persons within the bowl will experience no embarrassment due to the presence of the spectators, since the spectators will be quite invisible to them. On the other hand the spectators will have a clear view within the bowl, and generally the amusement derived by the spectators will be even greater than that which they would derive if the persons within the bowl could see them.
- At the centre of the bowl 1, the shaft 12 may be extended upwardly, and may carry a small circular platform 24. The provision of the platform 24 is intended to allow an official or other person in charge of the apparatus to stand at the centre point and collect tickets or generally supervise the persons within the bowl. As indicated in chain dotted lines at 25, ropes or the like may be arranged within the bowl so as to form a hand grip for persons within the latter.
- Persons within the bowl may amuse themselves in any desired manner, and wheeled carriages may be at disposal. In Figures 4 and 5 of the drawings, a tricycle is illustrated, such tricycle having a steerable front wheel 26 and a pair of rear wheels 27, the wheels 27 being carried in yokes 28 which are attached through pivots 29 to a main frame member 30. The member 30 has a sleeve 31 at its front side, for the reception of the shank 32 of a pair of front forks 33. The shank 32 has handlebars 34 secured to its upper end. The main frame member 30 is at its rear side formed to afford a seat 35. Balance weights 36 are secured at the lower ends of the yokes 28, so as to bring the centre of gravity of the tricycle below the axes of the wheels of the tricycle. In use, the tricycle may be pushed along by a person within the bowl, the handlebars 34 being used for steering as is customary with normal vehicles. The rear wheels 27 are connected caster-fashion to the main frame member 30, so that generally it will not be possible for the tricycle to topple over. The seat 35 allows the person using the tricycle to sit down when tired, the handlebars 34 then being utilized as a back support.
- The tricycle described above is intended mainly to give persons confidence, and it will also serve to allow persons to move down the walls when the drum slows up, the caster action back wheels allowing the tricycle to glide smoothly down the wall as the centrifugal force decreases, the balance weights 36 preventing any tendency to toppling.
- If desired the caster action on the back wheels may be dispensed with, pins being inserted to engage the fixed frame and the caster yokes.
- In Figures 6 and 7 a device similar to that illustrated in Figures 4 and 5 is shown. As before there are rear wheels 37 and 38 carried in caster yokes 39, such yokes being pivotally connected as at 40 with a main chassis member 41. The front side of the latter has a boss 42 traversed by a shank 43 carrying a pair of front forks 44 for the reception of the front wheel 45. The wheel 45 is supported on, and connected with, a shaft 45A upon which there is also seated a sprocket wheel 46. A sprocket wheel 47 is carried upon a shaft 48 journaled in a boss 49 provided at the upper end of the shank 43. A chain 50 connects the sprockets 47 and 46. The shaft 48 is at either end formed with crank handles 48A. The chassis member 41 carries a seat 51, the level of the seat being considerably below that of the axes of the wheels 37 and 45, so that when a persons is sitting upon the seat, the centre of gravity of the whole system lies below the plane containing said

axes. This will serve to prevent any tendency to toppling.

As will be readily understood, with the device shown in Figures 6 and 7 a person may sit upon the seat 51, and may cause the device as a whole to move by turning the crank handles 48A. Furthermore the device may be steered by turning the shaft 48 about the axis of the shank 43.

In Figure 2 of the drawings there is shown a further constructional embodiment of the amusement apparatus. In this case the bowl 53 is sunk into the ground, the ground level being indicated at 54. A main central bearing 55 is arranged below the bowl and a roller ring 56 is provided at the lower periphery of the bowl. The upper part of the apparatus consists of a closed structure 57 having windows as indicated at 58. There is a door 59 allowing persons to enter the upper structure, and an annular platform 60 is secured to the upper side of the bowl 53. The platform 60 carries a number of seats 61, which may be built to take one person or to take several as indicated at 61A. In Figure 3 the arrangement of the individual seats 61 is shown in further detail. Each seat is carried upon a trunnion member 62 secured to the annular platform 60. The seats have arms 63 pivotally secured at 64 to the trunnion support 62. The location of the pivot point 64 is such that when a person is sitting upon the seat, the centre of gravity is below the pivot point 64, so that under the action of centrifugal force when the platform 60 is rotated, the seat 61 assumes the position indicated in chain dotted lines in Figure 3.

As seen in Figure 2, the upper part of the bowl 53 is closed by a roof portion 65 having inserts of semi-transparent mirror glass 66. The annular platform 60 at its inner side carries an upstanding wall 67 which serves to prevent persons from falling upon the roof of the bowl. In this constructional modification, the drive from the bowl is obtained from an electric motor 68 arranged in the roof structure of the apparatus. The motor 68 drives a vertically disposed shaft 69 through the intermediary of a bevel pinion pair 70. The shaft 69 is connected with the upper part of the bowl 53 through struts 71.

The interior of the bowl is lighted by means of a central electric lamp 72 and by means of a plurality of peripherally arranged lamps 73. Lighting for the upper structure is afforded by small lamps 74 located at the junction of the platform 60 and the wall 67, so that the light afforded by such lamps does not fall directly upon the semi-transparent mirror glasses 66.

Persons intending to enter the bowl 53 may do so through a passage 75, which may also serve as the exit. As in the construction described with reference to Figure 1, persons entering the bowl 53 may mount the walls thereof as the bowl is rotated by the electric motor 68 through the intermediary of the shaft 69. In this case, however, the spectators who are seated in the chairs 61 or 61A are also swung round so that they incline inwardly and simultaneously obtain a view of the interior of the bowl through the glass 66, the persons within the latter being unable to see through the glass 66 which appears from the inside as a mirror.

The interior of the bowl 53 may be wholly or partly lined with frictional material to afford a grip on the working surface. Devices such as illustrated in Figures 4 to 7 may be introduced into the bowl to aid persons in mounting the walls. In order to lighten the construction of

the whole apparatus, it is preferable to make at least the bowl thereof from aluminum.

It will be appreciated that the upper part of the bowl may if so desired be left open. In Figure 1, there is illustrated in chain dotted lines an upward extension E on the bowl. The extension E may have inserts of semi-transparent mirror glass so that spectators may look down into the bowl without being visible to persons within the latter.

At the interior central portion of the bowl cupboards or the like may be arranged for the reception of articles which intending users of the bowl wish to give up for safe storage.

15 The glass windows 58 may be coloured or darkened so as to prevent too great a lighting intensity in the upper structure. As an alternative to the methods of driving the bowl indicated above, a transportable power unit may be located at the side thereof, and belting employed for the power transmission.

What I claim and desire to secure by Letters Patent in the United States is:—

1. Amusement apparatus comprising a bowl, a 25 closable entrance into said bowl to allow persons to reach the interior thereof, driving means for turning said bowl about a vertical axis, at least one gallery for spectators arranged adjacent the upper part of the bowl, and means for allowing 30 spectators to look into the bowl, said means simultaneously serving to prevent persons within the bowl, from seeing the spectators.

2. Amusement apparatus comprising a bowl, at least one closable entrance to said bowl to 35 allow persons to enter therein, driving means for turning said bowl about a vertical axis, at least one gallery for spectators arranged adjacent the upper side of the bowl, a screen arranged between the spectators' gallery and the bowl, said 40 screen having inserts of semi-transparent glass so that persons within the bowl cannot see the spectators whereas the spectators can see said persons.

3. Amusement apparatus comprising a bowl, at 45 least one closable entrance to allow persons to

enter therein, means for turning said bowl about a vertical axis, at least one gallery for spectators arranged adjacent the upper side of said bowl, a roof member closing the upper side of the bowl, peripheral inserts of semi-transparent mirror 5 glass in said roof member, and lighting means arranged to illuminate the interior of the bowl so that persons therein cannot see through said inserts which are, however, transparent to said spectators.

10 4. Amusement apparatus comprising a bowl, at least one closable entrance to said bowl to allow persons to enter therein, means for turning the bowl about a vertical axis, at least one gallery for spectators arranged adjacent the upper 15 end of the bowl and arranged to rotate therewith, and means to allow the spectators to view the interior of the bowl without, however, being visible to the occupants thereof.

5. Amusement apparatus comprising a bowl, 20 at least one closable entrance to allow persons to enter therein, means for driving the said bowl about a vertical axis, at least one gallery for spectators arranged adjacent the upper side of said bowl and arranged to turn therewith, seats 25 for the spectators in said gallery, pivotal supports for such seats whereby the spectators swing inwardly when the gallery turns with the bowl, and means for allowing the spectators to view the interior of the bowl without, however, being visible to the occupants thereof.

6. Amusement apparatus comprising a bowl, at least one closable entrance to allow persons to enter therein, means for rotating said bowl about a vertical axis, at least one gallery for spectators 35 arranged adjacent the upper side of the bowl and arranged to rotate therewith, a closure member for the upper side of said bowl, said closure member having peripheral inserts of semi-transparent mirror glass, and lighting means to illuminate 40 the interior of the bowl so that persons therein cannot observe the spectators whilst the spectators may view the interior of the bowl.

LEIF GÖSTA HELLESEN. 45
